Primary Examiner — Sandra Snapp*Assistant Examiner* — Ieisha Price(74) *Attorney, Agent, or Firm* — Hackler Daghighian Martino & Novak(57) **CLAIM**

The ornamental design for a screw, as shown and described.

DESCRIPTION

FIG. 1 is a perspective view of a screw embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict environmental subject matter, are for illustration only and form no part of the claimed design.

1 Claim, 4 Drawing Sheets(56)
